UNITED STATES PATENT OFFICE.

GEORGE O. RESHAW, OF ST. JOSEPH, MICHIGAN.

FRUIT-BASKET LID.

Application filed January 5, 1928. Serial No. 244,737.

The invention relates to covers for baskets such as those used in shipping apples, and it is the principal aim of such invention to provide a new and improved cover having 5 unusual flexibility and strength, allowing its peripheral hoop to be forced into contact with and held against the basket rim without danger of breaking said hoop loose from the cover slats, even though the fruit in the 10 basket may be rather highly crowned.

The cover herein disclosed is of a type in which one of the slats projects from the peripheral hoop for engagement with the usual basket handles, and while this slat 15 must be comparatively strong and thick, the remainder of the slats are formed of thin veneer for flexibility and inexpensive manufacture. The peripheral hoop also is rather thin and narrow for the same reasons, and 20 if the handle engaging slat were secured to this hoop, by nails or staples, there would be danger of splitting said hoop. Hence, it is a further aim of the invention to provide a 25 novel relation of parts whereby said handle-engaging slat will be properly held in place without the necessity of securing it to the hoop.

A still further object is to provide a cover having an attached liner of cardboard or 30 other desired yieldable material, which not only covers the lower sides of the slats but also covers the inner side of the above-named hoop, protecting the fruit from injury by said slats and hoop.

With the foregoing in view, the invention 35 resides in the novel subject matter herein-after described and claimed, the description being supplemented by the accompanying drawing.

Fig. 1 is a top plan view of the cover applied to a basket.

Fig. 2 is a vertical sectional view on line 2-2 of Fig. 1.

Fig. 3 is a fragmentary bottom plan view 45 of the cover.

Fig. 4 is an enlarged sectional view on line 4-4 of Fig. 1.

The form of construction herein disclosed may be considered as preferred, and while 50 this construction will be specifically described, it is to be understood that within the scope of the invention as claimed, variations may be made.

The peripheral hoop 5 of the cover is 55 formed of wood and is rather thin and nar-

row to permit free flexibility, said hoop being preferably of about eleven-sixteenths of an inch in width and five-thirty-seconds of an inch in thickness. Extending diametrically across the space circumscribed by this 60 hoop, are a number of thin veneer slats 6, these slats being preferably of about two inches in width and one-sixteenth of an inch in thickness. The slats 6 are freely flexible and are disposed in crossed relation, with 65 their ends spaced apart circumferentially, and said slats are so disposed as to form two diametrically opposite openings 7 of a width considerably greater than that of the remaining spaces between the slat ends. A 70 handle-engaging slat 8 of greater thickness than the slats 6, passes through the openings 7 and has its end portions disposed upon the upper edge of the hoop 5, the intermediate portion of said slat 8 being passed under 75 the intermediate portions of the thin veneer slats 6. A nail 9 or other desired fastening means passes through the central portions of the slats 6 and 8 and is clinched upon the lower side of the latter, tightly connecting 80 all of said slats with each other and at the same time holding said slat 8 against longitudinal sliding. This slat 8 is held against 85 edgewise movement by engagement with the slats 6 at opposite edges of the openings 7. The ends of the slat 8 project in the usual manner beyond the hoop 5, for engagement with the usual wire handles 10 of a fruit basket 11.

A basket cover having the characteristics 90 so far described, possesses numerous advantages. It may be easily and inexpensively manufactured, even from green wood, and whether such wood be still somewhat green or seasoned when the cover is put into use, said cover will be unusually flexible and hence the peripheral hoop 5 may be forced into contact with the basket rim 12 and held in contact with said rim by the usual means, even though the fruit in the basket may be 95 rather highly crowned. The thinness of the slats 6 and the hoop 5 is not only of advantage in permitting this unusual flexibility of the cover, but in effecting a great saving in cost of manufacture. On account of the 100 thinness of the hoop 5, it would be impractical to staple or nail the handle-engaging strip 8 against the upper edge of this hoop, as there would be severe danger of splitting 105 the latter. The construction shown and de- 110

scribed however, effectively maintains the strip 8 in proper place without the necessity of securing it to the hoop.

In the preferred form of construction, I 5 transversely score the end portions of the thin veneer slats 6 and turn the outer ends of said slats downwardly at 14, at the inner side of the hoop 5, and in order to reinforce these slats against possible breakage at the 10 weakened portions 13, I provide short reinforcing strips 15 of cardboard or other desired material. These strips lie upon the end portions of the slats 6 and are secured to them by staples or the like 16, and the 15 outer ends of said strips 15 are turned downwardly at 17 between the slat ends 14 and the hoop 5, said downwardly turned ends 14—17 being secured to said hoop, preferably by staples 18 passing through 20 these parts. This construction insures that the thin veneer slats 6 shall not break loose from the hoop 5, when the cover is being applied to a basket in which the fruit is rather highly crowned. The cover may, if 25 desired, be manufactured in a somewhat crowned form as shown in Fig. 2, but this is not essential.

A liner 19 of cardboard or any other desired yieldable material, covers the lower 30 sides of the slats 6—8 and has its peripheral edge 20 turned downwardly against the inner sides of the downwardly turned ends 14 of the slats 6, said peripheral edge being split at 21 to facilitate downward turning 35 of said edge. While the edge 20 may be secured in any desired manner, the free ends of the staples 18 preferably pass through said edge and are clinched thereon, as shown in Figs. 2 and 4. Thus, in addition to covering the slat ends 14 and the inner side of the hoop 5 to prevent them from injuring the fruit, it will be seen that the flange 20 acts as a washer between the clinched ends 40 of the staples 18 and the ends 14 of the thin veneer slats 6, overcoming any danger of splitting said slat ends when clinching the staples and moreover insuring that said ends shall be more tenaciously anchored than if the staples were clinched directly against 45 said ends.

If desired, in addition to the fastening means 18 passing through the flange or downturned edge 20 of the liner 19, one or more tacks or the like 22 may connect the 50 central portion of this liner with the slat 8, and if desired, the fastener or fasteners 22 may be of a length to extend also through the central portions of the slats 6.

Preferably, the liner 19 is formed with 55 openings 23 communicating with the spaces between the numerous slats, for purpose of ventilation.

In addition to possessing the advantages above pointed out, the novel construction 60 herein disclosed, is such that it may be read-

ily manufactured by machine operations. Before downward bending of the ends 14 of the slats 6, the reinforcing strips 15 may be secured to said ends by the staples or the like 16. Then, when all of the slats 6 are assembled, the ends 14 of the slats 6 and the outer ends 17 of the reinforcing strips 15 may be readily bent downwardly, incident to application and anchorage of the hoop 5 by mechanical means, the liner 19 being placed in position before the driving of the staples 18, so that these staples may be driven through all of the parts 5—17—14—20.

On account of the excellent results obtainable from the details disclosed, such details are preferably followed. However, within the scope of the invention as claimed, variations may be made and while I have disclosed a number of advantageous features embodied in a single basket cover, it is to be understood that said features may be advantageously used independently of each other.

I claim:

1. A basket cover comprising a hoop, a plurality of slats having their ends turned downwardly and disposed at the inner side of said hoop, a yieldable liner covering the lower sides of said slats and having a downwardly turned edge contacting with the inner sides of said downwardly turned slat ends, and fasteners passing through said hoop, said slat ends and said liner edge; said downwardly turned liner edge constituting a washer between which and said hoop said slat ends are securely held.

2. A basket cover comprising a plurality of slats of veneer having downwardly turned ends, short reinforcing strips secured upon the upper sides of said slats at the outer end portions of the latter, said strips having downwardly turned outer ends lying against the outer sides of said downwardly turned slat ends, a hoop lying against said downwardly turned strip ends, a yieldable liner covering the lower sides of said slats and having a downwardly turned edge lying against the inner sides of said downwardly turned slat ends, and fasteners passing through said hoop, said downwardly turned strip and slat ends, and said downwardly turned liner edge.

3. A basket cover comprising a hoop, crossed slats having their ends secured to said hoop, said slats being disposed to provide two diametrically opposed openings, a handle-engaging slat passing through said openings and having its end portions disposed upon the upper edge of said hoop, the intermediate portion of said handle-engaging slat being disposed under said crossed slats, and means holding said handle-engaging slat against endwise movement, said slat being held against edgewise move-

ment by the slats at the edges of said openings.

4. A basket cover comprising a thin freely flexible wooden hoop, crossed slats of thin freely flexible veneer having downwardly turned ends secured to a vertical side of said hoop, said slats being circumferentially spaced at their ends and disposed to provide two diametrically opposite openings of 10 greater width than the remaining spaces between the slat ends, a handle-engaging slat of greater thickness than said veneer slats, said handle-engaging slat passing through said openings and having its end portions

disposed upon the upper edge of said hoop, 15 the intermediate portion of said slat being disposed under said veneered slats, and fastening means passing through said veneer and handle-engaging slats; said fastening means holding said handle-engaging slat 20 against endwise movement, edgewise movement of this slat being prevented by the portions of the crossed slats at opposite sides of said openings.

In testimony whereof I have hereunto af- 25 fixed my signature.

GEORGE O. RESHAW.
